SAW-TOOTH WAVE GENERATOR

Walter J. Howarth, Trenton, N. J., assignor to
Radio Corporation of America, a corporation of
Delaware

Application February 1, 1949, Serial No. 73,972

1 Claim. (Cl. 250—36)

1

This invention relates to recurring waveform generators and more particularly to linear saw-tooth generators for cathode ray beam deflection circuits and the like.

The simplest form of saw-tooth wave generator takes the form of a circuit arrangement wherein a capacitive element is charged through a resistance element. A switch, preferably of the electronic type, is connected across the capacitive element to periodically and quickly discharge the capacitive element. The long sloping portion of the saw-tooth wave then occurs during the charging portion of the cycle while the short and steep portion of the saw-tooth wave occurs during the discharge portion of the cycle.

It immediately becomes apparent, however, that the charging or long slope of the saw-tooth wave is non-linear because the resistor causes the capacitor to charge exponentially, that is the current through the charging resistor does not remain at a constant level.

It has been heretofore proposed therefore to employ, instead of a resistor, a constant current device such as an electron discharge device of, for example, the pentode type which passes a substantially constant current over a large range of applied anode voltages.

The simple neon tube which has been employed as a means for discharging the capacitive element has heretofore been replaced by trigger circuits involving electron discharge devices. However, a practical generator trigger circuit capable of operating satisfactorily over a wide range of frequencies and other conditions may require the employment of several independent electron discharge devices.

When it is desired to reduce the number of electron discharge devices to economize, it is sometimes proposed to dispense with the constant current device employed for charging the capacitive element. In this latter arrangement, however, the loss of linearity becomes serious. It may also be possible to reduce the number of electron discharge paths or tubes by eliminating or reducing the number of tubes in the capacitive element discharge circuit. But such arrangements are inefficient even to the extent of failing at high frequencies.

According to this invention a circuit arrangement is provided employing only two electron discharge devices of the triode or pentode type which has substantially linear saw-tooth wave output characteristics. The circuit is also capable of operation over a wide frequency range.

One controllable electron discharge device is employed for charging a capacitor while a sec-

2

ond electron discharge device not only discharges the capacitor but also cuts off the current in the charging tube.

A primary object of this invention is to provide for the generation of linear saw-tooth waves.

Another object of this invention is to provide a circuit arrangement operable over a wide range of frequencies for generating linear saw-tooth waves.

Another object of this invention is to provide a simple saw-tooth wave generator of high efficiency.

Other and incidental objects of the invention will be apparent to those skilled in the art from a reading of the following specification and an inspection of the accompanying drawing wherein there is illustrated, by circuit diagram, one form of this invention.

Turning in more detail to the drawing there is shown a first electron discharge device or tube 1 and a second electron discharge device or tube 3.

Although tubes 1 and 3 are shown as triodes they may take the form of pentodes and although they are shown schematically as separate tubes they may be contained in the same envelope without departing from the spirit of this invention.

An anode potential is applied to the anode of tube 1 through resistance 5.

A condenser 7 is connected between the cathode of the electron discharge device 1 and a point of fixed potential such as "ground" 9. An output circuit is connected to the cathode of tube 1.

The anode of tube 3 is connected to the control electrode of tube 1 and a resistance element 11 is connected between the control electrode and cathode of tube 1.

In the particular form of the invention shown in the drawing, a resistance 13 is placed in the cathode circuit of tube 3.

The control electrode of tube 3 is connected to the anode of tube 1 through a condenser 15. A grid leak type resistance 17 is connected to the control electrode of tube 3.

The synchronizing signal for timing the oscillator is applied to the control electrode of tube 3 through a coupling condenser 19 and a resistance 21.

The operation of the device shown in the drawing may best be understood if the circuit arrangement is compared to the basic saw-tooth wave generator referred to above and including a capacitive element which receives its charge through a resistor and wherein a switch is connected across the capacitive element to quickly discharge it periodically.

In the circuit arrangement shown, condenser 7 is the capacitive element, tube 1 is the charging resistance or constant current device. In this connection the operating potentials may be chosen so that the tube 1 is operating above the "knee" portion of its characteristic curve. That is, in the portion of its curve which is substantially constant current regardless of the applied voltage. As stated above in another form of this invention, tube 1 may be of the pentode variety.

Tube 3 then is employed as a discharge circuit.

Let it be assumed that the cathodes of both tubes are emitting and a B plus potential is applied to the anode of tube 1. Condenser 7 will charge-up due to the current flow through tube 1. As the condenser 7 charges, the anode of tube 1 will rise in potential. After it has risen a certain amount, the control electrode of tube 3 becomes sufficiently positive to cause tube 3 to become conductive.

It might be stated here, that due to grid current in tube 3, condenser 15 has assumed a charge which prevents tube 3 from becoming conductive until the anode potential of tube 1 rises to a high plus value.

When tube 3 becomes conductive, condenser 7 discharges through tube 3. The discharge current flowing through resistance 11 provides a negative bias on the control electrode of tube 1 so that tube 1 is cut off. Condenser 7 continues to discharge until the current through resistor 11 decreases to the point to permit tube 1 to again conduct at which time the control electrode of tube 3 is driven in a negative direction cutting off tube 3 which in turn reduces the negative bias on the control electrode of tube 1 so that it proceeds to charge condenser 7 at a substantially linear rate.

It will be seen from this explanation that tube 3 not only functions to discharge the capacitive element 7, but it serves also to control the charging tube.

Thus it will be seen that a linear saw-tooth wave may be formed by employing two simple electron discharge devices 1 and 3 and a circuit arrangement is easily controllable over a wide range of frequencies.

Although it is not intended that the invention should be limited to the tube types and circuit values listed below, they are listed by way of example only. The particular tube types and circuit constants shown are suitable for employment in a saw-tooth wave generator adaptable as a horizontal oscillator in television deflection circuits wherein the frequency is in the neighborhood of 15,000 cycles per second.

Electron discharge devices 1 and 3	6SN7
Resistance 5	ohms 50,000
Condenser 7	mfd .025
Resistor 11	ohms 150
Resistor 13	do 200
Condenser 15	mfd .005
Resistor 17 (variable)	megohms 2
Condenser 19	mfd .00025
Resistor 21	ohms 500,000

D. C. voltage measurements (VTVM):

Anode (tube 1)	V	270
Anode (tube 3)	V	260
Control electrode (tube 1)	V	260
Control electrode (tube 3)	V	-40
Cathode (tube 1)	V	260
Cathode (tube 3)	V	+.2
Total current	ma	1.5

Having thus described the invention, what is claimed is:

A saw-tooth wave generator comprising in combination, first and second electron discharge devices, each of said devices having a cathode, an anode and at least one control electrode, an output condenser, said condenser being connected between the cathode of said first discharge device and a point of fixed reference potential, a line resistor, a terminal adapted to be energized from a source of operating potential, said resistor being connected between said terminal and the anode of said first discharge device, a fixed grid resistor, said grid resistor having a relatively low impedance whereby saw-tooth waves are assured and being connected between the control electrode and cathode of said first discharge device, a direct current connection between the grid of said first discharge device and the anode of said second discharge device, a cathode resistor, said cathode resistor having a relatively low impedance and being connected between the cathode of said second discharge device and said point of fixed reference potential, a variable grid resistor, said variable resistor having a relatively high impedance and being connected between the control electrode of said second discharge device and said point of fixed reference potential, a coupling condenser, said coupling condenser being connected between the control electrode of said second discharge device and the anode of said first discharge device, an input resistor, said input resistor having a relatively high impedance, an input condenser, said input condenser being adapted to be energized from a source of synchronizing signals, said input resistor being connected between said input condenser and the control electrode of said second discharge device and means for connecting an output circuit across said output condenser.
